(57) **CLAIM**

The ornamental design for an automobile, as shown and described.

DESCRIPTION

1. Automobile

1.1 is a front perspective view of an automobile in which the clothes management machine for drying clothes is in a retracted position and hidden inside the backseat;

1.2 is a front elevation view thereof;

1.3 is a rear elevation view thereof;

1.4 is a left side elevation view thereof, to which the right side elevation view is a mirror image thereof;

1.5 is a top plan view thereof;

1.6 is an enlarged and partial front perspective view thereof;

1.7 is a front perspective view thereof in which the clothes management machine is in an extended position and pulled out from the backseat;

1.8 is a top plan view thereof in which the clothes management machine is in an extended position and pulled out from the backseat;

1.9 is an enlarged and partial front perspective view thereof in which the clothes management machine is in an extended position and pulled out from the backseat; and

(Continued)

1.10 is an enlarged and partial top plan view thereof in which the clothes management machine is in an extended position and pulled out from the backseat.

The broken lines in the reproductions illustrate portions of the automobile that form no part of the claimed design.
